CLAIM

The ornamental design for an axillary crutch, as shown and described.

DESCRIPTION

FIG. 1 is a front, bottom perspective view of an axillary crutch, showing my new design;

FIG. 2 is a rear, top perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is a front, bottom perspective view of the axillary crutch of FIG. 1 in a partially extended configuration;

FIG. 10 is an enlarged view of the area labeled 10 in FIG. 1;

FIG. 11 is an enlarged view of the area labeled 11 in FIG. 1; and,

FIG. 12 is an enlarged view of the area labeled 12 in FIG. 1.

The dashed lines in the figures illustrate portions of the axillary crutch that form no part of the claimed design.

The dash-dot broken lines represent stitching that forms no part of the claimed design.

The dot-dash-dot broken lines of the axillary crutch in FIG. 1 illustrate a boundary and cut line of the enlarged view in FIG. 10 and form no part of the claimed design.

The dot-dash-dot broken lines of the axillary crutch in FIG. 1 illustrate a boundary and cut line of the enlarged view in FIG. 11 and form no part of the claimed design.

(Continued)

The dot-dash-dot broken lines of the axillary crutch in FIG. 1 illustrate a boundary and cut line of the enlarged view in FIG. 12 and form no part of the claimed design.
